United States Patent Office

Des. 195,720
Patented July 23, 1963

195,720

DOOR HANDLE

Courtney A. Leubner, Forest Park, Ill., assignor to Amerock Corporation, Rockford, Ill., a corporation of Illinois

Filed Feb. 11, 1963, Ser. No. 73,495

Term of patent 14 years

(Cl. D10—8)

FIG. 2 is an end view of the handle.

FIG. 3 is a side view of the handle as viewed from the left in FIG. 1.

FIG. 4 is a side view of the handle as viewed from the right in FIG. 1.

FIG. 5 is an enlarged sectional view taken along the line 5—5 in FIG. 1.

FIG. 6 is an enlarged sectional view taken along the line 6—6 in FIG. 5.

I claim:

The ornamental design for a door handle, substantially as shown.
